UNITED STATES PATENT OFFICE

GUSTAF A. OSTLING AND CARL L. GUSTAFSON, OF CHICAGO, ILLINOIS

DESIGN FOR A PICTURE FRAME

Application filed December 7, 1932. Serial No. 46,319. Term of patent 7 years.

To all whom it may concern:

Be it known that we, GUSTAF A. OSTLING, and CARL L. GUSTAFSON, citizens of the United States, residing at 5140 Nevada Street, Chicago, in the county of Cook and State of Illinois, have invented a new, original, and ornamental Design for a Picture Frame, of which the following is a specification, reference being had to the accompanying drawing, forming a part hereof.

Figure 1 is a front elevational view showing our new design.

Figure 2 is a plan view.

Figure 3 is a side elevational view.

Fig. 4 is a perspective view to a somewhat reduced scale.

We claim:

The ornamental design for a picture frame, substantially as shown.

GUSTAF A. OSTLING.
CARL L. GUSTAFSON.
